Attorney

UNITED STATES PATENT OFFICE.

CLARENCE J. LUTHER, OF POYNETTE, WISCONSIN, ASSIGNOR TO THE C. J. LUTHER COMPANY, OF PORT WASHINGTON, WISCONSIN.

GRINDING-MACHINE.

SPECIFICATION forming part of Letters Patent No. 593,964, dated November 16, 1897.

Application filed April 19, 1897. Serial No. 632,763. (No model.)

To all whom it may concern:

Be it known that I, CLARENCE J. LUTHER, a citizen of the United States, and a resident of Poynette, in the county of Columbia and 5 State of Wisconsin, have invented certain new and useful Improvements in Grinding-Machines; and I do hereby declare that the following is a full, clear, and exact description thereof.

10 My invention has for its object to simplify and cheapen the manufacture of machines especially organized for grinding knife-sections on sickle-bars of mowers and reapers, as well as to increase their durability and 15 provide for their utilization as grinders for edge-tools of various kinds other than those aforesaid. Hence it consists in certain peculiarities of construction and combination of parts hereinafter set forth with reference 20 to the accompanying drawings and subsequently claimed.

Figure 1 of the drawings represents a side elevation of my improved grinding-machine, partly in vertical longitudinal section, as indicated by lines 1 1 in Figs. 2 and 3; Fig. 2, 25 a front elevation of a portion of the machine, partly in transverse section, as indicated by line 2 2 in Fig. 1; Fig. 3, a plan view, partly in horizontal section, as indicated by line 3 3 30 in Fig. 1; and Fig. 4 a rear elevation of a portion of the machine, partly in transverse section, as indicated by line 4 4 in Fig. 1.

Referring by letter to the drawings, A represents a cast-metal base provided at its corners with apertures for screws or bolts b, by 35 which it may be made fast to a bench or other support, if desired. Cast in one piece with the base A are a pair of upwardly-projecting lugs c and a transverse angular ledge B, the 40 latter being provided with a V-shaped notch and having its upper surface beveled. The base - ledge B projects under a grinding-wheel, hereinafter particularly set forth, and constitutes a support for the sickle-bar 45 of a mower or reaper, the bevel of its upper surface being such that the proper slant is given to said sickle-bar when the knife-sections thereof are being ground, the V-shaped notch in said base-ledge affording room for 50 the grinding-wheel to move forward between a pair of said knives when operating to

sharpen the same. A pivot-rod C is run through the base-lugs c and other lugs d, depending from a cast-metal tilt-plate D, that is herein shown as having a wooden handle 55 E attached thereto, although it may be found practical to cast the tilt-plate with a handle. The pivot-rod C is shown as having a head e at one end and its other provided with screw-threads for the engagement of a nut f; but 60 it is practical to simply upset both ends of said rod to thereby make permanent the simple economical connection of the base and tilt-plate.

One of the lugs d of the tilt-plate is provided with a depending rear stop g, that comes to rest on the base A when said plate is swung back, and projecting forward from said lug is shown an ear h, in which a stop-screw F has its adjustment with reference to said base, 70 whereby forward throw of the aforesaid tilt-plate is regulated or prevented.

The tilt-plate is provided with a boss i at its upper end, and held fast in this boss by a set-screw j is a rod G, with which lugs k at 75 the upper end of a preferably two-part grinding-wheel-supporting frame have pivotal connection. The rod G also constitutes an arbor for a loose spur-wheel H, of comparatively large diameter, that is provided with 80 a crank-handle I and has mesh with a pinion J, that is fast to another arbor K, having its bearings in lower arms m of said frame. The pinion J has greater width of face than the spur-wheel H in mesh therewith, and provision is had for longitudinal play of the arbor K in its bearings, so that the grinding-wheel L, fast on said arbor, may automatically adjust itself to knife-sections of a sickle-bar, 85 supported on the base-ledge B, above specified, this grinding-wheel being of conical form 90 in opposite directions from its longitudinal center.

The upper part M of the frame, to which reference is had in the foregoing, is offset at 95 its lower end, and this offset portion is provided with longitudinal slots for the engagement of clamp-bolts n, that extend forward from the lower part M' of said frame. By having the aforesaid frame in two parts longitudinally adjustable one upon the other provision is had for properly meshing the 100

driving-gear above specified and to compensate for wear on the part of said gear.

A set-screw N has adjustment in the pivotal frame against a stud p on the forward side of the tilt-plate D, and thus said frame is set so as to insure of the grinding-wheel L coming properly on its work, it being understood that said tilt-plate and frame in pivotal connection therewith move together when the handle E is operated.

A spiral tension-spring P is connected at its ends to the tilt-plate and frame in pivotal connection therewith to insure pressure of the grinding-wheel L when the latter is operating upon knife-sections of a sickle-bar, and it is to be observed that the spring has movement with said plate and frame, as well as expansion and contraction, this being one of the particular features of my construction and arrangement of parts designed to preserve the normal tension of said spring. While the spring P may be connected in various ways to the tilt-plate and pivotal frame, it is preferable, as herein shown, to provide said plate and frame with apertures through which the eye ends of said spring are passed and engaged by transverse stay-pins r r', the former pin being adjustable in two series of notches that flank the longitudinal edges of the aperture in the aforesaid tilt-plate, this aperture being of greater length than the one in the aforesaid frame. By the adjustment of the stay-pin r the tension of the spring P is regulated, and it is to be understood that the greater the slant of said spring the greater resistance it has to the frame that is in pivotal connection with the tilt-plate, whereby the grinding-wheel is caused to exert correspondingly greater pressure on sickle-bar knife-sections and more rapidly grind the same when the machine is in operation.

The V-slotted sickle-bar clamp-plate Q herein shown has a longitudinal slot s, engaged by a pivot-stud t on the cast-metal base of the machine, and a thumb-nut R is run on the screw-threaded end of the stud against the clamp-plate to bind the latter in working position, the sickle-bar being steadied on the bevel-faced V-notched ledge of said base by transverse shoulders u, depending from said clamp-plate.

The proper adjustment of the stop-screw F will prevent the grinding-wheel from coming into detrimental contact with the thumb-nut R when the handle E of the tilt-plate D is pulled forward, and this provision for limiting movement on the part of said tilt-plate also prevents straining of the tension-spring P, above specified.

The arbor K, on which grinding-wheel L is made fast, is extended beyond one of the frame-arms in which it has bearing and provided with a rigid collar w, against which another grinding-wheel S may be clamped by means of a set-nut x, run on the screw-threaded extremity of said arbor extension, the latter grinding-wheel being for work on

edge-tools of various kinds other than knife-sections of a sickle-bar.

The grinding-wheel S is an attachment for the machine above specified, and it is not positioned on the arbor K when said machine is utilized for grinding knife-sections of a sickle-bar, as otherwise it would have detrimental contact with the ledge B, constituting part of the machine-base.

It being desirable to utilize the grinding-wheel S, the set-screw F is adjusted to come against the machine-base and thereby prevent forward movement of the tilt-plate. It also follows that the set-screw N may be adjusted to elevate the frame that has pivotal connection with said tilt-plate and carries the arbor K, common to both grinding-wheels.

Having thus described my invention, what I claim as new, and desire to secure by Letters Patent, is—

1. A grinding-machine having a cast-metal base in one piece with a pair of upwardly-extending lugs and a V-notched bevel-top sickle-bar support, a sickle-bar clamp-plate in suitable connection with the base, a tilt-plate having lugs in pivotal connection with the base-lugs, an arbor supported by the tilt-plate, a frame in pivotal connection with the arbor, suitable means for effecting positive pivotal adjustment of the frame, a spiral spring connected at its ends to said tilt-plate and frame to move therewith coincident with its expansion and contraction, a grinding-wheel having its arbor rotative in bearings constituting parts of the frame, a pinion fast on the latter arbor, and a driving spur-wheel loosely mounted on the former arbor to mesh with said pinion.

2. A grinding-machine having a tilt-plate provided with a depending rear stop that comes to rest on the base of the machine, an adjustable stop arranged to limit forward movement of the tilt-plate, an arbor supported by the tilt-plate, a frame having positive pivotal adjustment on the arbor, a spiral spring connected at its ends to said tilt-plate and frame, a grinding-wheel having an arbor rotative in bearings constituting parts of the frame, a pinion fast on the latter arbor, a driving spur-wheel on the former arbor having mesh with the pinion, a transverse bevel-top V-notched ledge on the machine-base, and a clamp mechanism for a sickle-bar supported on said ledge.

3. A grinding-machine having a tilt-plate, an arbor supported by the same, a frame having positive pivotal adjustment on the arbor, a spiral spring connected at its ends to the tilt-plate and frame to move therewith coincident with its expansion and contraction, a grinding-wheel having an arbor in rotative connection with said frame, a pinion fast on the latter arbor, a driving spur-wheel on the former arbor in mesh with the pinion, a transverse bevel-top V-notched ledge on the machine-base, and a clamp mechanism for a sickle-bar supported on said ledge.

4. A grinding-machine having a tilt-plate, an arbor supported by the same, a frame in positive pivotal adjustment on the arbor, a spiral spring having one end thereof in adjustable connection with the tilt-plate longitudinally of the same and its other end in non-adjustable connection with the frame although movable with both, a grinding-wheel having an arbor in rotative connection with said frame, a pinion fast on the latter arbor, a driving spur-wheel on the former arbor having mesh with the pinion, a transverse bevel-top V-notched ledge on the machine-base, and a clamp mechanism for a sickle-bar supported on the ledge.

5. A grinding-machine comprising a tilt-plate and means for locking the same in swung-back position, an arbor supported by the tilt-plate, a frame in spring connection with said tilt-plate and having positive pivotal adjustment on the arbor, a sickle-bar

supporting ledge and clamp on the machine-base, an arbor rotative in the frame and having one of its ends extended from said frame for the engagement of a detachable grinding-wheel when said tilt-plate is locked in swung-back position, a grinding-wheel fast on the frame-supported arbor for work on sickle-bar knife-sections when the aforesaid tilt-plate is free to be swung forward, a pinion fast on the latter arbor, and a driving spur-wheel loosely mounted on the former arbor to mesh with the pinion.

In testimony that I claim the foregoing I have hereunto set my hand, at Poynette, in the county of Columbia and State of Wisconsin, in the presence of two witnesses.
